INVENTOR

William Gorman

United States Patent Office.

WILLIAM GORMAN, OF NEW BRITAIN, CONNECTICUT, ASSIGNOR TO RUSSELL & ERWIN MANUFACTURING COMPANY, OF SAME PLACE.

Design No. 3,916, dated March 22, 1870.

DESIGN FOR ESCUTCHEONS FOR DOORS.

The Schedule referred to in these Letters Patent and making part of the same

To all whom it may concern:

Be it known that I, WILLIAM GORMAN, of New Britain, in the county of Hartford and State of Connecticut, have originated and designed a new Design for Flush Escutcheon for Sliding Doors; and I do hereby declare that the following is a full, clear, and exact description thereof, reference being had to the accompanying drawings making a part of this specification.

The outer edge of the escutcheon and the edge of the finger-recess are surrounded by a raised band, *a*, whereby the effect of a sunken panel is given to that portion of the escutcheon which is designated as *A*.

The space between such raised band-lines is filled

in with scroll-work, *b b b*, in relief, upon a plain or matted ground.

The base-plate *B* of the escutcheon is also ornamented with leaf-work radiating from the key-hole opening, as shown.

What I claim as my invention, and desire to secure by Letters Patent, is—

The design for a flush escutcheon for sliding doors, of the character substantially as herein shown and described.

WILLIAM GORMAN.
